UNITED STATES PATENT OFFICE.

WALTER HAMIS GLOVER, OF LEAMINGTON, AND CHARLES FRED TOPHAM, OF COVENTRY, ENGLAND, ASSIGNORS TO COURTAULDS LIMITED, OF LONDON, ENGLAND.

PRODUCTION OF ARTIFICIAL SILK.

Application filed October 29, 1928, Serial No. 144,994, and in Great Britain January 7, 1928.

This invention relates to the production of artificial silk when using the dry spinning process that is to say a process in which a cellulose ester of an organic acid or a cellulose ether is dissolved in a volatile solvent and the solution is then passed through a jet or drawplate containing the requisite number of holes into a space containing warm air or other gas whereby the solvent 10 is volatilized leaving the cellulose compound in the form of filaments. As an example of such process may be mentioned the spinning of a solution of cellulose acetate in acetone into a space containing warm air.

15 In the method of producing artificial filaments from cellulose acetate by the dry spinning process, as hitherto practised, the filaments, issuing from the holes in the jet have been led on in association through and out 20 of the chamber containing warm air, and have then been wound up in the form of a thread onto a bobbin either directly or with the interposition of a twisting device.

According to our invention we have found 25 that a thread of artificial silk obtained by the process of dry spinning can be collected and twisted simultaneously by means of the centrifugal action of a spinning box rotating at high speed.

30 In carrying out this invention, the thread which leaves the spinning chamber is preferably passed round a delivery roller, and then into the spinning box, with a reciprocating funnel, as described for example in 35 the specification of British Letters Patent No. 23,158, A. D. 1900, in order to distribute the thread evenly in the box, unless the said box is comparatively shallow, in which case the funnel can be dispensed with. It is 40 generally preferred to moisten the thread slightly, before it reaches the spinning box, and this can be effected by passing the thread over a brush, which is kept damp. This assists the introduction of the thread into 45 the box and also helps to keep the thread in correct position and to form a satisfactory cake. If desired, the thread can be sized on its way to the spinning box, by passing it over a suitable surface, or through a brush, 50 which is maintained moistened with a solution of size such, for instance, as a dilute solution of gelatine. It is, of course, desirable to remove the sized thread from the box before the size has set sufficiently to bind 55 the different coils of thread together.

The introduction of the first end of the thread into the spinning box can be effected in any suitable manner. For example, as is shewn diagrammatically in the accompanying drawing, as the thread A, which is being delivered at a comparatively rapid speed of say 120 yards or more per minute, is taken up by or passes over one or more of the rollers B, a loop C of the said thread A can be led, by thread guide α^1 over a smooth groove d cut across one end of a pipe or tube D, to the other end of which is attached means for blowing a current of air or other gas through the said tube. The tube is held with the end thereof across which the thread 60 passes adjacent to the reciprocating funnel E, so that when a sharp downward movement is given to the said tube D the loop of thread is broken and a current of air being passed along the tube from the other end, 65 the broken end of the thread which is continuous with the thread delivered from the spinning chamber is blown down the funnel E into the spinning box F. The thread which follows from the delivery roller continues 70 passing down the funnel, and the process is allowed to continue, until the box F is sufficiently full.

The thread can be taken out of the box in any convenient manner but unless the cake 85 be subjected to some special treatment while in the box as hereinafter described it is generally preferred not to take the cake of thread out as a whole, in the manner which is practised when collecting wet-spun viscose, 90 or cuprammonium artificial silk in a centrifugal box, but to leave the cake in the box, and draw out the thread singly, preferably through the funnel E, through which it entered the box. In this case, however, the 95 funnel is preferably not allowed to reciprocate, but is maintained in one position, such that the lower end thereof is situated about opposite to the center of the cake. The thread may be then withdrawn from the 100 box either while the box is stationary, or while it is rotating, and in this latter case, the advantage is obtained of putting an additional twist onto the thread. If however, the box, with the cake in it, be heated for 105 a short time, for instance, in the case of an aluminium box, for about ten minutes at 70° centigrade, the cake can then be easily removed from the box, while still retaining its original shape, and the thread can be wound 110

off from the outside of the cake onto a reel or bobbin.

What we claim is:—

1. The production of artificial silk by passing a solution of a cellulose ester of an organic acid, or a cellulose ether in a volatile solvent through a jet or drawplate into a space containing warm air or other gas, whereby the solvent is volatilized leaving the cellulose compound in the form of filaments, then leading the filaments in association from the warm space and collecting them in a rapidly rotating spinning box.
2. In the production of artificial silk according to the foregoing first claiming clause, the method of introducing the end of the thread into the rapidly rotating box by blowing it in with a current of air or other gas.
3. The production of artificial silk by passing a solution of a cellulose ester of an organic acid, or a cellulose ether in a volatile solvent through a jet or drawplate into a space containing warm air or other gas, whereby the solvent is volatilized, leaving the cellulose compound in the form of filaments, then leading the filaments in association from the warm space, passing a loop of the running thread, the ends of which loop are on the delivery roller, over a smooth groove cut in the end of a tube, placing this end of the said tube adjacent to the reciprocating funnel of a rotating spinning box,

giving a sharp downward movement to the said tube and simultaneously passing a current of air or other gas through the tube, whereby the thread is broken and the end thereof is caused to pass down the funnel into the box.

4. The production of artificial silk by passing a solution of a cellulose ester of an organic acid or a cellulose ether in a volatile solvent through a jet or drawplate into a space containing warm air or other gas, whereby the solvent is volatilized, leaving the cellulose compound in the form of filaments in association from the warm space, then slightly moistening the filaments and collecting them in a rapidly rotating spinning box.

5. The production of artificial silk by passing a solution of a cellulose ester of an organic acid, or a cellulose ether in a volatile solvent through a jet or drawplate into a space containing warm air or other gas, whereby the solvent is volatilized, leaving the cellulose compound in the form of filaments, then leading the filaments in association from the warm space and collecting them in a rapidly rotating spinning box, then applying suitable heat to the box containing the cake of thread in order to facilitate the removal of the cake from the box.

In testimony whereof we have signed our names to this specification.

WALTER HAMIS GLOVER.
CHARLES FRED TOPHAM.
